UNITED STATES PATENT OFFICE

OLAUS T. HODNEFIELD, OF LOS ANGELES, CALIFORNIA

DIAGONAL-WEAVE WALL BOARD

Application filed February 28, 1927. Serial No. 171,433.

My invention relates to wall-board which is used in buildings. The wall-board is secured to the wall studs or ceiling joists for forming a base for plaster. It is very desirable that the wall-board will not buckle on the wall when the plaster is applied thereto; therefore, the wall-board must not expand when the plaster is applied to it, or if it does expand it must be made so that this expansion will not cause buckling.

It is an object of my invention to provide a wall-board which will not buckle when the plaster is applied to it.

Another requirement of a good wall-board is that it be designed so that the plaster may be securely keyed to it; otherwise there is a liability of the plaster falling from place or creeping, due to its own weight or from vibration.

It is accordingly another of the objects of this invention to provide a wall-board to which the plaster will securely key itself.

It is important that the wall-board be rigid and strong so that it will form a good base for the plaster; and it is one of the objects of my invention to provide a wall-board which has rigidness and strength when attached to the supporting members of the wall or ceiling.

Other objects and advantages of the invention will be made evident in the following description which is taken in connection with the drawing.

Referring to the drawing,

Fig. 1 represents a sheet of material which forms a part of a preferred form of my invention.

Fig. 2 is a view illustrating the preferred form of wall-board of my invention secured to a wall.

Fig. 3 is a section taken on the line 3—3 of Fig. 2.

Fig. 4 is a section taken on the line 4—4 of Fig. 3.

Fig. 5 is a section similar to Fig. 4 but showing plaster applied to the wall-board.

Fig. 6 is a view of a second form of my invention secured to a wall.

Fig. 7 is a view of a third form of my invention secured to a wall.

The form of my invention shown in Figs. 1 to 5 inclusive has a sheet of material 11. This sheet 11 may be made of various substances such as cardboard, wood, or even metal if desired. In the preferred form of 55 the invention the sheet is made of a cardboard or other paper composition which is chemically treated so as to be fireproof. As illustrated best in Fig. 1 which shows the sheet per se, diagonal slots 12 are cut in the 60 sheet. The slots 12 are arranged in diagonal rows as shown, and the adjacent ends of slots of each row are separated by bridges 13. The rows of slots divide the sheet 11 into a plurality of parallel diagonally extending strips 14. The ends of the slots 12 of alternate rows terminate in horizontal planes A—A so that the bridges formed between the ends of these slots rest in the same horizontal plane. The ends of the slots of the 70 other rows of slots terminate in horizontal planes B—B which extend parallel to the horizontal planes A—A but are in staggered relationship. The ends of the slots of adjacent rows of slots overlap in a horizontal 75 plane as illustrated; for example, the upper end of one slot overlaps with the lower end of a slot in an adjacent row. At the central part of each slot 12 is an expansion joint 17 which is formed by cutting notches 18 in 80 adjacent strips 14.

The wall-board, as illustrated best in Figs. 2 and 3, also includes lacings 20 which may be made of different materials but are preferably formed of wood or chemically treated 85 cardboard. These lacings 20 extend in horizontal planes and through the overlapping ends of the slots 12. The purpose of the lacings 20 is to bend adjacent portions of each strip 14 in opposite directions so that each strip is wave-shaped as illustrated in Fig. 3. The lacings 20 are extended over alternate strips 14 and under the other strips 14 so that a sort of a wave is provided. Each slot 12 in the preferred form of my invention is long 90 enough to have a lacing 20 extended through each end thereof. At the central part of each of the slots 12 the adjacent strips 14 are extended in crossing planes. Before the lacings are placed the strips all rest in a com- 100

mon plane, and the expansion notches 18 are likewise in a common plane. When the adjacent strips are bent into a wave shape by the lacings 20, the adjacent strips where they cross the normal plane of the sheet 11 are crossed as previously mentioned, and the expansion notches 18 of each expansion joint 17 are disaligned so that side walls 21 thereof are in different planes. The purpose of this is to permit an expansion of the sheet 11 without buckling, a further explanation of which will be made later.

Adverting particularly to Fig. 2, it will be seen that the lacings 20 extend in horizontal planes at right angles to vertical studs 22 which form a part of the wall construction. The wall-board is attached to the studs 22 by nails 23 which are driven through the lacings 20 into the studs. The lacings 20 provide a rigid support for the sheet 11 since they are secured to the vertical studs 22. The extending of the lacings 20 in a horizontal plane is an important part of this invention because of the fact that rigidity is thereby obtained. A further feature of the construction illustrated in the figures in consideration is that the slots 12 extend diagonally; that is, neither horizontally nor vertically. The advantage resulting from this feature is that plaster when applied will securely key to the wall-board. The reason is that the slots are not vertically disposed. If the slots were vertically disposed, the plaster would tend to slide downward, since the wave-strips 14 would offer no opposition; consequently the plaster would creep and be very uneven, and in many cases would free itself from the wall-board. In Figs. 4 and 5 I illustrate a portion of the wall-board and one of the expansion joints 17. In Fig. 4 the plaster has not been applied. In Fig. 5 I show a coating of plaster 26 applied to the wall-board. If the wall-board is made of cardboard, the expansion thereof will be very small, and the wall-board will have an appearance not very dissimilar to that shown in Fig. 4. On the other hand, if the wall-board is made of wood, the expansion will be quite material and the wall-board will have an appearance as shown in Fig. 5. The adjacent strips 14 expand laterally so that bottoms 27 of the slots 18 move towards each other, and if the expansion is great enough will come into contact. This expansion is permitted by reason of the fact that the notches 18 are disaligned so that the side walls 21 thereof are in different planes and will not contact when this expansion occurs. This feature of the invention is very important and permits the wall-board to be made of a cheap wood material if desired. Without expansion joints of this nature the wall-board cannot be made of wood because considerable buckling would result when the edges of the adjacent strips 14 came into contact with each other.

The form of the invention, just described, is adapted for use on vertical walls or on ceilings or on horizontal walls. When the wall-board is used on a ceiling, the lacings 20 extend across the joists and are nailed thereto substantially as shown in Fig. 2. When the wall-board is used in this manner the direction of extension of the slots and lacings 12 and strips 14 respectively are immaterial. The direction of extension of these slots and strips, however, are extremely important when the wall-board is used in a vertical position as shown in Fig. 2. The forming of slots and strips diagonally with respect to the lacings is a material departure from any other wall-board on the market today or known to the inventor.

In Fig. 6 I show a second form of my invention. This form of the invention includes a sheet 40 which, as in the first form of my invention, is preferably made of a fire-proofed cardboard. The sheet 40 has slots 41 formed therein which are arranged in diagonal rows, the slots of each row being separated by bridges 42. In this form of the invention the slots 41 are rather short, and the bridges of each of the rows of slots are in aligned horizontal planes. The slots of adjacent rows of slots are not overlapped as in the first form of the invention. Extended through the slots 41 are lacings 43 which serve the purpose of bending strips 44 formed between the rows of slots into a wave-shaped form of substantially the same shape as in the first form of the invention. The important difference between the form of the invention now being described and the first form of the invention previously described is that the slots are quite short and only long enough to have a single lacing 43 extended therethrough, the lacings being extended through the central parts of the slots. In this form of the invention no expansion joints are provided. This form of the invention is adapted primarily for wall-board which is not intended to be made of a material which will expand when plaster is applied thereto. The slots 41, however, are open so that a slight amount of expansion may occur without any buckling.

In Fig. 7 I illustrate a third form of my invention which has a sheet 50 in which slots 51 are formed. The slots 51 are formed in rows of slots which are parallel, the slots of each row being separated by bridges 52. In this form of the invention the slots all extend vertically and are separated by vertical strips 53. The slots are not overlapped as in the first form of the invention, and the bridges between the slots of the different rows of slots are in horizontal alignment. Lacings 55 are extended through the slots of the different rows of slots, and the strips 53 are bent into wave shape as in the other forms of the invention. In this form of the invention

tion the lacings 53 extend horizontally, and the wall-board is as rigid as in the other forms of the invention. The wall-board illustrated in Fig. 7 is primarily adapted for 5 use on ceilings and wherever the wall-board rests in a horizontal plane. It is not well adapted, however, for vertical walls since there is a liability of the plaster creeping and falling from place.

10 I claim as my invention:

1. In a wall-board, the combination of: a sheet having slots cut therein, said slots being in rows and separated at their ends by bridges, there being strips formed between 15 said rows of slots; and lacings extended through said slots for bending adjacent portions of the same strips in opposite directions, said lacings being extended alternately over and under said strips.

20 2. A combination as defined in claim 1 in which said strips and said slots extend diagonally with respect to said lacings.

25 3. In a wall-board, the combination of: a sheet having slots formed therein, said slots being in diagonal rows separated by parallel diagonal strips, said slots of each row being separated by bridges, and the ends of said slots of adjacent rows overlapping in a horizontal plane; and lacings extended through 30 said slots, each of said lacings being in a horizontal plane and extending through said overlapping ends of said slots.

35 4. A combination as defined in claim 1 in which said strips and said slots extend diagonally with respect to said lacings, and said slots each having two lacings extending through them.

40 5. In a wall-board, the combination of: a sheet having diagonal slots formed therein, thus forming a plurality of diagonal strips; and lacings extending through said slots for bending said strips in opposite directions, said lacings extending at angles to said strips, which angles are less than ninety degrees.

45 In testimony whereof, I have hereunto set my hand at Los Angeles, California, this 17th day of February, 1927.

OLAUS T. HODNEFIELD.
